UNITED STATES PATENT OFFICE.

BENJAMIN H. ALVEY, OF LOUISVILLE, KENTUCKY, ASSIGNEE, BY MESNE ASSIGNMENTS, TO THE ALVEY-FERGUSON COMPANY, OF OAKLEY, CINCINNATI, OHIO, A CORPORATION OF OHIO.

CONVEYER.

1,144,337.

Specification of Letters Patent. Patented June 22, 1915.

Application filed August 6, 1907, Serial No. 387,264.

To all whom it may concern:

Be it known that I, BENJAMIN H. ALVEY, a citizen of the United States, residing at Louisville, in the county of Jefferson and State of Kentucky, have invented certain new and useful Improvements in Conveyers, of which the following is a specification.

My present invention has for its object the production of a gravity conveying system by means of which boxes, barrels or other packages may be placed upon the conveyer and be delivered thereby to any one of various different places, under the control of an attendant located at some central 10 station or controlling point.

In pursuance of this object it comprises a plurality of runs or sections extending in different directions from a common supplying section or run which is provided with a switch section adapted to be moved to connect the supplying section with either one of said plurality of sections, said switch section being provided with adjusting means running to a convenient place for 20 operation. In the best and most complete embodiment of the invention there will be a series of such switches and the actuating means therefor will extend to a common operating point.

As herein embodied the system embraces severally new and useful features which cooperate to produce a system of the utmost efficiency.

The invention therefore consists in certain peculiarities in the construction and arrangement of parts, and in certain novel combinations of elements substantially as hereinafter pointed out in the subjoined claims.

In the accompanying drawings I have illustrated what is at present regarded as the best embodiment of the invention, and in said drawings:

Figure 1 is a plan view of the gravity conveying system embodying what is arbitrarily herein termed a main run, a series of supplemental runs extending in different directions from the main run and switches having operating means extending to a central operating or switch controlling station. Fig. 2 is a transverse section on the line 2—2 of Fig. 1, looking in the direction of the arrow. Fig. 3 is a side elevation of a portion of the system showing one of the 50 sections elevated.

The same characters of reference designate the same parts in the several views.

In producing a system such as herein contemplated, a number of sections A, B, C, are relatively arranged to produce what is herein termed, arbitrarily, main and supplemental runs including switches adapted to connect with the main or the supplemental runs at will.

For convenience the main run is considered to be formed of a plurality of sections A arranged to provide a space (or a plurality of spaces, at intervals) between them; the switch sections B are arranged in such space or spaces and considered to normally 65 form a part of the main run, and the supplemental runs are considered to be formed of the sections C and to extend off in varying directions from different points of the main run contiguous to the ends of the 70 switch sections and the spaces referred to.

It should be understood that it is desirable to deliver packages by gravity conveying systems, sometimes to one place and sometimes to another place. For example, 80 it may in one system be desirable to deliver certain packages to a door or a car located at one side of the building, other packages to a door or car located at the opposite side of the building, and still other packages to 85 some other place. In other systems it may be desirable to deliver packages variously to any one of a number of rooms or storage places on the same floor. It is of course not necessary to describe herein, or to show in 90 the drawings, all the various requirements and arrangements to suit the same, as it is thought to be sufficiently apparent from the foregoing that a system having what may be arbitrarily termed a trunk or main line or run and a supplemental run leading off at an angle therefrom, or a series of such supplemental runs leading off variously from the main run, with suitable provision for the connecting of the latter with or disconnecting them from the main run or 95 trunk line, is important.

It is thought that it will be further apparent that the present invention is not restricted to any particular detail, relative location of sections, or number of such sections, as these will vary to suit various requirements of use.

Each section A, B and C is provided with freely rotatable rollers *a* and is ar- 110

ranged at a downward inclination so that packages placed thereon will move by gravity with a minimum of friction and with a minimum of liability of the breakage of the contents. As herein shown, each section is composed of side elements a' which are secured together at intervals by transversely extending straps a^2 ; and the rollers a extend continuously across the section and have their ends journaled in the side elements a' and their intermediate parts of concave formation. The rollers in the bends or turns of the system are of greater diameter at their outer ends than at their inner ends.

Each section is preferably of a portable nature and is provided with a suitable support, and these sections are removably secured together in such relation to each other as to form a system of the character hereinbefore described.

Each switch section B is pivotally mounted at one end. The pivot thereof is preferably located at one side of the section, as indicated at b . Suitable means are provided for swinging these switch sections B from the main run to the supplemental run, or from the supplemental run back to the main run. Any desirable means for this purpose may be employed. The one herein shown consists of a rope, cable, or other flexible device b' leading over properly arranged guide pulleys b^2 to one side of the section B from a suitable place, and a similar flexible device b^3 leading over rollers b^4 from said place to the other side of the switch section. It will be understood that each section is similarly provided with these actuating means and is independently operable thereby, and that said actuating means will preferably extend to a common central or controlling station.

The section supports D which are arranged at the junctions of the main and supplemental runs comprise a top plate d which is mounted upon suitable legs d' preferably connected transversely of the sections by the piece d^2 . This top plate d is long enough to extend entirely across the junction of the main and supplemental sections and is broad enough to support the contiguous ends of the several sections A, B and C and to form a base upon which the switch section B will travel in its movement from one to the other run. If it be desired, said switch section may be provided with supporting rollers d^3 adapted to traverse said top plate, to thereby permit it to be adjusted with maximum ease and said rollers may engage a track d^4 (Fig. 1) upon the top plate.

It will be noted that when either switch section is adjusted to connect the corresponding supplemental run with the main run, as shown in dotted outline in Fig. 1,

the gap between the pivoted end of the adjusted switch section and the end of the main line section adjacent to said pivoted end is bridged by the top plate of the support at the junction of the switch section 70 and main line section.

It may sometimes be desired to extend one of the sections across a door or other object, entrance to which it is undesirable to unnecessarily obstruct. Therefore, for the 75 purpose of exemplifying a way of minimizing this disadvantage, I have shown in the accompanying drawings one of the sections C as mounted to swing sidewise in a vertical plane. It is of course assumed that 80 this is the obstructing section. This section and the contiguous section A are provided with a special support E comprising a top member e which extends from the outer side of one section to the outer side of 85 the other section and is provided between the sections with a hinge e' . The plate d upon which the ends of said sections A and C are mounted also is provided between said sections with a hinge e^2 or said end of 90 the section C may be otherwise hingedly secured. The leg or legs of the support which are arranged under the section C are hinged, or pivotally connected, with the section so as to be capable of being turned down on 95 said section when the latter is elevated.

From the foregoing the advantages and structure of the present invention will be readily comprehended and it will be apparent that the invention is not restricted 100 to the detail construction or arrangement of parts shown, said construction and arrangement being merely exemplary of one of several which are contemplated to be within the scope and spirit of the invention set 105 forth in the subjoined claims.

Having thus described the invention what I believe to be new and desire to secure by Letters Patent, and what I therefore claim is:—

1. A conveying system comprising a first and a second section having contiguous ends and arranged at an angle with each other, each of said sections being inclined and provided with freely rotatable rollers to support 115 the packages, a third section similarly inclined and provided with freely rotatable rollers, said third section arranged with one end separated by a space from the junction of the two first mentioned sections, and a 120 pivoted switch section provided with freely rotatable rollers and arranged in said space, with one of its ends contiguous to the end of the third section and its other end at said junction and movable into line with either 125 the first or the second section.

2. A conveying system comprising a main trunk line having a break in its length, and a curved line leading off from one end of said break, each of said lines being inclined 130

and provided with freely rotatable rollers to support packages, and a switch section arranged in said break and inclined and provided with freely rotatable rollers, the last 5 mentioned section being pivotally mounted and adapted to close the break in the main line or to break the continuity of the main line and connect the portion thereof on one side of the break with the curved line, for 10 the purposes described.

3. A conveying system comprising a main trunk line having a break in its length, and a curved line leading off from one end of said break, each of said lines being inclined 15 and provided with freely rotatable rollers to support packages, and a switch section arranged in said break and inclined and provided with freely rotatable rollers, the last mentioned section adapted to form a part 20 of the main trunk line, and being pivoted at one end and having its other end provided with a means for moving it into and out of position in which the continuity of the main trunk line is broken and a section of the latter 25 is connected with the curved line.

4. A gravity conveying system having a series of sections relatively arranged to form inclined main and supplemental runs, a pivoted switch section arranged contiguous to 30 ends of said runs and adjustable to communicate with either of the same, each of said sections having freely rotatable rollers upon which the packages travel, and a support arranged under contiguous ends of sections 35 of the main and supplemental runs and upon which the end of the switch section moves.

5. In a gravity conveying system, a plurality of sections relatively arranged to form 40 inclined main and supplemental runs, a switch section pivotally mounted at one end and having its other end adapted to communicate with contiguous ends of sections of either the main or supplemental runs, 45 each of said sections having freely rotatable rollers upon which the packages travel, a support for contiguous ends of the sections of the main and supplemental runs, and upon which said other end of the switch section 50 is adapted to travel, and rollers between said support and switch section.

6. A gravity conveying system having sections provided with freely rotatable rollers for the packages, one of said sections being 55 hinged at its side to its support, and adapted to turn sidewise into approximately vertical plane.

7. A gravity conveying system having sections provided with freely rotatable rollers 60 for the packages, one of said sections being

hinged at its side to its support, and adapted to turn sidewise into approximately vertical plane, said section having a hinged supporting leg adapted to be turned into position against the same.

8. A gravity conveying system having a plurality of sections relatively arranged to provide main and supplemental runs, each of said sections having freely rotatable rollers for the packages, and a transversely arranged support extending from one section 70 to the other and hinged between the same.

9. A gravity conveying system comprising inclined package-carrying sections separated from each other and each provided with side 75 elements and freely-rotatable rollers, a supplemental section arranged at an angle to the first-mentioned sections and having an end adjacent to an end of one of the same, and a switch-member provided with similar 80 rollers and side elements and arranged in the space between the first-mentioned sections and adapted to be swung to a position between one of the same and the supplemental section, said switch member being piv- 85

oted at one side of its end, the pivot being located adjacent to the end of one of said

first-mentioned sections and at a point outside the side element thereof and on the side

nearest the supplemental section. 90

10. A gravity conveying system comprising inclined package-carrying sections separated from each other provided with side elements and freely-rotatable rollers, a supplemental section arranged at an angle to the first- 95 mentioned sections and having an end adjacent to an end of one of the same, and a switch-member provided with similar rollers and side elements and arranged in the space between the first-mentioned sections and 100 adapted to be swung to a position between one of the same and the supplemental section, said switch member being pivoted at one side of its end, the pivot being located adjacent to an end of one of said first-men- 105 tioned sections and at a point outside the side element thereof and on the side nearest the supplemental section, and a supporting member arranged at the junction of one of the first-mentioned sections and the pivoted 110 end of the switch-member and adapted to close the gap between the switch-member and the said section.

In testimony whereof I affix my signature, in presence of two witnesses.
